UNITED STATES PATENT OFFICE.

ROBERT H. BARKER, OF CHAMBERSBURG, PENNSYLVANIA.

GRAIN-SCOURING APPARATUS.

Application filed December 8, 1924. Serial No. 754,609.

This invention is an apparatus for washing, drying and hulling various kinds of grain, preparatory to milling the same.

One of the objects of the invention is to provide a simple means for introducing the grain into the apparatus, in measured quantities of predetermined volume. A further object is to provide means for introducing a washing and scouring fluid simultaneously with the introduction of the grain. A further object is to provide a plurality of treating chambers, and means for automatically effecting transfer of the grain from one chamber to another, in timed sequence.

The invention will be hereinafter fully set forth and particularly pointed out in the claims.

In the accompanying drawings:

Figure 1 is a front elevation, with parts broken away, illustrating an apparatus constructed in accordance with the invention. Figure 2 is an end view of the apparatus. Figure 3 is a detail view illustrating the feed hopper and its adjuncts, parts being in section. Figure 4 is a side elevation. Figure 5 is a sectional view illustrating the apparatus for controlling the washing fluid. Figures 6 and 7 are side and front views respectively, of one of the grain valve gates.

Figure 8 is a detail view illustrating the operating connection of a pair of valve gates. Figure 9 is a detail view of one of the operating cams. Figure 10 is a sectional view illustrating one of the chambers.

Referring to the drawings, the main supporting frame work consists of two end frames 10, rigidly connected by top and bottom bars 11 and 12, respectively. Supported by the main frame work are a plurality of working chambers 13, 14, 15, 16, 17 and 18, which are separated from each other by division plates or partitions 19, suitably secured to the top and bottom bars.

In each compartment is rotatably mounted a grain moving device, preferably in the form of a fan or beater 20, said beaters being carried by a main shaft 21, mounted in suitable bearings 22, and driven by means of a pulley 23, from any desired source of power. The beaters 20 may be of any preferred construction, but are shown as consisting of drums rotatably mounted upon the shaft 21, and provided with peripheral rims having radially disposed projections, which may be made of any ma-

terial sufficiently rigid to act to carry the grain around and also to create the necessary air displacement. While six chambers are shown, it is to be understood that the number of chambers may be increased or diminished as desired, without departing from the spirit of the invention. In practice, the casings 13, 14 and 15 are provided with perforated walls 24, enclosing the beater 20, and the casings 16 and 17 are provided with suitable abrasive walls 25, enclosing the beaters, for the purpose of hulling the grain if such operation is desired.

The partition walls 19 are each provided with an opening 26, by means of which the grain may be passed from one chamber to another. In order to effect the change automatically during the operation of the apparatus and in timed sequence, a pair of flow controlling and transfer gates 27 are mounted in each chamber in parallel relation, and so disposed that they engage the peripheral walls of the chamber in a position to guide the grain laterally through the opening in the chamber, under the action of the centrifugal force developed in the operation of the beater 20. Said gates are pivotally supported as indicated at 28, and conform to the curvature of the periphery of the chamber, as clearly indicated in Figure 7. Each pair of gates 27 are moved in unison by means of levers 29, one for each gate 27, connected thereto in suitable manner.

The levers 29 extend to the outside of the casing, and the levers of each pair are connected by a link 30, which is provided with rollers 31, positioned to engage a cam 32, secured to a cam shaft 33, mounted in suitable bearings 34, and operatively connected with the main shaft 21. The cams 32 are so positioned that the gates are automatically operated in timed sequence, so that once the apparatus is charged with grain the operation will be practically continuous. Leading from each of the working chambers is a stack 34, which communicates with a common exhaust pipe 35, or if desired the stacks from the hulling chambers may be connected with separate exhaust flues.

The grain is introduced into the chamber 13 through a hopper 36, which is secured in position in suitable manner, and is provided with an inlet slide valve 37 and an outlet slide valve 38, said valves being suitably connected by an operating lever 39, pivoted to

the frame work. The lever 39 is actuated by a crank disk 40 connected with said lever through a link 41.

The crank disk 40 is secured to a shaft 42, 5 mounted in a casing 43, which is provided with a water inlet 44 connected to a source of supply, not shown. Said casing is also provided with a water outlet 45, communicating with the chamber 13. Mounted on 10 the shaft 42, and located between the inlet 44 and the outlet 45, is a valve disk 46 having openings, preferably two, 47 and 48, respectively. The shaft 42 is rotated by means of a gear 49 secured thereto and meshing 15 with a train of gears indicated at 50, driven in suitable manner from the main shaft 21.

In operation, the shaft 21 is rotated through the medium of a pulley 23, and as a consequence the cam shaft 33, and the valve 20 shaft 42 are rotated through the medium of 25 the intermediate gearing. The parts are so proportioned that they will operate in timed sequence, the valve gate 37, being held open until the hopper 36 is filled with grain. In 25 this connection it is to be understood that the volume of the hopper 36 is approximately the same as the capacity of any one of the working chambers.

When the hopper 36 is filled, the crank 20 disk 40 operates to close the valve 37, and open the valve 38, thereby depositing the grain into the chamber 13. Immediately after the grain is deposited in the chamber 13, the opening 47 in the valve disk 46, registers with the passage between the inlet opening 43 and the outlet opening 44, of the casing 42, permits the introduction of a charge of water into the chamber 13.

The beater 20, rotating rapidly within the 40 chamber 13, scours the grain and forces on the water and dirt through the perforations in the plate 24. In the meantime, the disk 46 continues to rotate and brings the opening 48 into register with the openings 44 and 45, 45 thereby introducing a second charge of water into the chamber 13, which serves to rinse and more completely cleanse the material. Immediately after this takes place, the first cam 32 engages the roller 31 of the valve 50 actuating mechanism of the chamber 13, bringing the gate members 27 to an inclined position, thereby uncovering the opening in the partition 19, so as to direct the grain laterally from the chamber 13 into the chamber 14, due to the action of the centrifugal 55 force developed in the operation of the beater 20.

By the time that the chamber 13 is emptied 60 the hopper 36 has again been filled and will recharge the chamber 13. In the meantime the grain is caused to travel around in the chamber 14 until additional moisture is forced out through the perforated plates 24, and the valves are actuated to transfer the 65 grain to the chamber 15. The cams are so

positioned that as the operation continues the grain is automatically transferred from one chamber to another, in time to permit the chamber being emptied to receive a new charge.

The chambers 16 and 17 are preferably 70 provided with abrasive walls, and the beaters 20 therein are faced with abrasion metal, which have the effect of removing the hulls as the grain travels through, and finally the 75 grain is discharged from the chamber 18 in a form ready for immediate milling, having been thoroughly cleansed, dried and hulled, by centrifugal force containing no moisture other than that normally present in the grain 80 had it not been treated by the apparatus described. All of the lighter dust, dirt and 85 hulls are drawn up into the stacks which are connected with exhaust apparatus of a type well-known in the art.

The advantages of the invention will be 85 readily apparent to those skilled in the art to which it belongs. It will be readily understood that the grain is introduced into the apparatus in measured quantities and 90 these quantities are thoroughly scoured by washing fluid introduced with the grain. The chambers are so arranged and the cam mechanism so related that the grain is automatically transferred from one chamber to 95 another in timed sequence, so as to maintain a continuous operation, each chamber being emptied before a new charge is introduced. By treating the grain in successive compartments, the grain and washing fluid are first 100 held in intimate relation, the scouring functions are effectively carried out in a minimum of time. Little or no water gets into the second chamber and as it progresses through the apparatus is thoroughly dried, 105 no scouring water reaching the third chamber.

Having thus explained the nature of the invention and described an operative manner of constructing and using the same, although without attempting to set forth all of the forms in which it may be made, or all of the forms of its use, what is claimed 110 is:—

1. A grain scouring apparatus comprising 115 a plurality of chambers having laterally disposed openings establishing communications between the respective chambers, agitator members mounted in the respective chambers, pivotally-supported laterally-120 movable cam controlled gates arranged in pairs, and means for periodically moving the gates of each pair in unison.

2. A grain scouring apparatus comprising 125 a plurality of chambers having laterally disposed openings establishing communication between the respective chambers, agitator members mounted in the respective chambers, pivotally-supported laterally-movable 130 cam controlled gates arranged in pairs, oper-

ating arms for said gates, links connecting the arms of each pair of gates, and moving means positioned to periodically engage said operating arms in timed sequence.

5. 3. A batch grain treating machine, comprising a housing structure formed with a plurality of independent inter-communicating batch compartments, an agitator rotatable in said housing and forming an inner 10 annular closure for all of said batch compartments to provide a plurality of independent annular batch compartments in said housing, agitating means on said agitator member operating in each of said compartments, and flow controlling and transfer means operable in each of said compartments to control the flow of the batch of material into the compartments and for transferring the batch of material from one 15 compartment to the next.

4. A batch grain treating machine comprising, a substantially cylindrical casing formed with a plurality of independent batch compartments, a cylindrical rotor member mounted in said housing and cooperating therewith to close said independent batch compartment to form annular compartments in the housing, agitating means operable in each compartment mounted on said cylindrical rotor, and flow controlling and transfer gates pivotally mounted in said housing in each of said batch treating chambers, said gates being movable laterally to the transverse plane of said housing, and chambers for effecting the axial flow of material in said batch chambers and transferring said batches from one chamber to the next.

5. A batch grain treating machine, com-

prising a plurality of independent batch chamber sections, means assembling said chamber sections in axial aligned relation, a cylindrical rotor mounted in said assembled sections and cooperating therewith to form annular batch chambers in each section in 45 independent relation, and flow controlling and transfer gates operable in each of said batch chambers for controlling the flow of the batch in each chamber axially of said machine, and for transferring a batch from 50 one chamber to the next in a predetermined manner.

6. A batch grain treating machine, comprising a cylindrical sectional housing having the sections forming annular batch 55 chambers and assembled in aligned relation, and a cylindrical rotor member rotatable in the housing cooperating with said sections to form a plurality of axially aligned annular batch treating chambers.

7. A batch grain treating machine, comprising a cylindrical sectional housing having the sections forming annular batch chambers and assembled in aligned relation, and a cylindrical rotor member rotatable in 65 the housing cooperating with said sections to form a plurality of axially aligned annular batch treating chambers, agitating means operable in each of said batch chambers, independently operable flow controlling and 70 transfer means in each of said chambers governing the axial flow of material in said chambers, and means operating said last mentioned means in predetermined timed relation.

In testimony whereof I have hereunto set my hand.

ROBERT H. BARKER.
